BY *McNamee* ATTORNEY

UNITED STATES PATENT OFFICE

RICHARD F. SCHULZKE, OF PORTLAND, OREGON

IRON HOLDER

Application filed February 10, 1930. Serial No. 427,228.

My invention relates to iron holders for ironing boards and has for its particular object the provision of an iron holder of simple outline, which is thus inexpensive to manufacture and one which is easily installed upon the board, which does not interfere with the ironing operation and which, when installed, functions as a partial protector for the end of the ironing board.

10 A more specific object of my invention is to provide a folding ironing table with a convenient iron holder arranged at one end of the board, which iron holder is adapted to serve as a convenient gripping element for 15 manipulating the parts of the board and has a wearing plate upon such end for protecting the surface of the board when the table is arranged upon end when being set up and collapsed.

20 This application embodies in part the matter divided out of my co-pending application for patent entitled "Ironing table", filed June 21, 1928 by myself, which application bears Serial No. 287,161, and in part is a 25 continuation and improvement upon the device shown in such application.

The details of construction and operation of an ironing table embodying my invention and the details of the iron holder are 30 illustrated in the accompanying drawing, in which:

Fig. 1 is a side elevation of such table with the collapsible support shown extended and with portions broken away to show the locking device;

Fig. 2 is a plan view of such table looking from the underside with the support for such table shown collapsed against the underside of the board;

Fig. 3 is a fragmentary, perspective view of my improved iron holder taken in a vertical plane extending longitudinally of the board and adjacent one edge of said holder; and

Fig. 4 is a fragmentary, sectional view thereof taken substantially on the line 4—4 in Fig. 3.

An ironing table embodying my improved iron holder comprises a board *a* mounted upon a collapsible support. Such support

comprises a rear leg structure *b*, composed of two spaced members *b'* connected by two horizontal slats *c* and *c'* and reinforced by slats *c2* and *c3* extending substantially longitudinally of such leg structure, and a diagonal 55 crutch *d*, also made up of two converging members *d'*. Such members *b* and *d* are pivotally connected to the rear end of the ironing board, being fastened thereto by cleats *e* depending from the under surface of 60 such board and extending substantially longitudinally thereof. A shaft or pivot pin *f* extends transversely of such board thru such cleats and serves as a common pivot connection for the ends of both such members *b* 65 and *d*. The converging members *d'* of the diagonal crutch *d* are secured at their point of convergence by a threaded screw *g* and are spaced apart adjacent such screw by a spacer *h*. Near the diverging end of such crutch is another spacer *h'*. Between such spacers *h* and *h'* are two spaced guide rods *i* extending laterally of such crutch and defining a groove *i'* between them. A jointed brace member *j* serves to hold the various members of the 70 ironing board in rigid extended position and the ends of such jointed brace members are pivotally fastened to the under surface of the board *a*, and the leg *b* respectively. The pivotal connection between the end of the 75 jointed brace member *j* and the board *a* is made thru two downwardly depending cleats *k* fastened to the under surface of the board *a* at substantially its middle. Such cleats are connected to the end of the member *j* thru a 80 pivot pin *k'*. The opposite end of such jointed brace member *j* is connected to the leg *b* by a pivot pin *l* extending thru such end and thru the reinforcing slat members *c* and *c'*. One element *j'* of such jointed brace 85 member *j* extends substantially horizontally when the table is arranged in set-up position and extends thru the groove *i'*. The other element *j2* of such brace member extends substantially vertically and such members *j'* and *j2* are connected by an integral fitting *m*. Such fitting *m* is substantially U-shaped in section, thus forming a channel, and such fitting *m* straddles the member *j'*, the webs *m'* of such fitting extending downwardly along 90 95 100

the sides of the member. Such webs are substantially longer than the thickness of the member j' and the portions extended beyond the undersurface of such member carry a bayonet joint n therein. The member j' is cut away at n' in registration with the portions of such joint n , which overlies such member j' . Upstanding integral ears $m2$ are arranged upon the back of such fitting and a pivot pin o extends thru such ears and thru the member $j2$ to pivotally connect the members of such jointed brace. Such bayonet joint n is adapted to engage the lowermost rod i defining the groove i' when the parts are arranged in set-up position, and a spring-like keeper p also engages such lowermost rod i and holds the same in the portion n' of such bayonet joint. Such keeper preferably is made of a spring-like leaf carried by the member j' . Two screws q fasten such keeper to the member j' , the screw q' being adjustable to vary the pressure exerted by such keeper and thus to vary the amount of pressure necessary to unseat the member i and to collapse the table.

A recess r is formed at the rear end of the ironing board a , entering such end approximately equi-distant from the sides thereof. A marginal shoulder s is formed about such recess and heat-resisting material t , such for example as asbestos, is arranged upon such shoulder s .

My improved holder u is carried in such recess with the outstanding edges supported upon such heat-resisting material and recessed so that the upper face of the iron holder is substantially flush with the active surface of the ironing board a . Nails v fasten the iron holder in place in such recess. Such iron holder u has a depressed portion u' formed therein forming a receptacle for the iron. The end $u2$ of such holder extends downwardly over the end of the ironing board a and is bent back upon itself to engage the undersurface thereof, as is shown in Fig. 2, thus virtually clamping the ironing board between the two spaced parallel portions. Such iron holder is made of an integral stamping and the portions are arranged so that the burrs formed by such stamping can be arranged to face the ironing board both on the top as well as on the bottom and thus such iron holder does not have to be dressed to remove such burr, which is quite sharp. This is one of the more important advantages attained by the bending over of the rear portion of the iron holder. Such bent over portion $u2$ also serves solidly to connect the iron holder to the board without depending upon nails. Such iron holder frequently is used as a gripping element for moving such iron board about, when setting up or collapsing the table and thus unless such iron holder is securely fastened to the board it will be unseated. Unseating permits the asbestos or

other heat-resisting material to shift from off the shoulder and to become lost so that the heat transmitted by the metal iron holder u chars the wood and destroys its seat in the board.

When arranging the table to be set up or collapsed, the table is supported upon the squared end of the board and thus the portion $u2$, which substantially encircles the end of the board, serves as a wearing element to protect the wooden portion of the board.

I claim:

1. In an ironing board having a shouldered recess entering from one edge portion, an iron holder arranged in said recess and engaging the shouldered portion thereof, said iron holder comprising an integral receptacle depending into the recess, having one edge extending across the open side of said recess, overlying the sides of the latter, depending downwardly, and terminating in an inwardly extending return flange thereby engaging the under surface of the board, and means extending thru the holder and into the shouldered portion of the board holding said inwardly extending flange against lateral displacement.

2. In an ironing board having a shouldered recess entering from one edge portion, an iron holder arranged in said recess and engaging the shouldered portion thereof, said iron holder comprising an integral receptacle depending into the recess, having one edge extending across the open side of said recess, overlying the sides of the latter, depending downwardly, and terminating in an inwardly extending return flange thereby engaging the under surface of the board, separate heat resisting material covering said shouldered portion of the recess upon which the iron holder is seated, said inwardly extending flange thereby preventing said holder from being lifted upwardly from the shouldered portion to release said heat resisting material.

3. In an ironing board provided with a recess in one edge portion thereof, a metallic iron holder overlying said recess, means securing said holder to the upper face of said board adjacent the edges of said recess, said iron holder including a downwardly inclined flange extending over the edge of said board and spanning said recess, said flange terminating in an inturned portion engaging in clamping relation the under surface of said board at the sides of said recess.

4. In an ironing board provided with a recess in one edge portion thereof, a metallic iron holder overlying said recess, means securing said holder to the upper face of said board adjacent the edges of said recess, said iron holder including a downwardly inclined flange extending over the edge of said board and spanning said recess, said flange terminating in an inturned portion engaging in

clamping relation the under surface of said board at the sides of said recess, said holder being unsecured to the edge of said board.

5. In an ironing board provided with a recess in one edge portion thereof, a metallic iron holder overlying said recess, means securing said holder to the upper face of said board adjacent the edges of said recess, said iron holder including a downwardly inclined 10 flange extending over the edge of said board and spanning said recess, said flange terminating in an inturned portion engaging in clamping relation the under surface of said board at the sides of said recess and a sharp 15 marginal burr formed upon the face of said holder opposing the faces and edge of said board, which burr is sheathed by said board under the influence of the securing means for said holder.
